UNITED STATES PATENT OFFICE.

ALEXANDER E. KEITH, OF HINSDALE, ILLINOIS, ASSIGNOR TO AUTOMATIC ELECTRIC COMPANY, OF CHICAGO, ILLINOIS, A CORPORATION OF ILLINOIS.

TELEPHONE TRANSMITTER.

1,412,080.

Specification of Letters Patent. Patented Apr. 11, 1922.

Application filed April 14, 1917. Serial No. 161,947.

To all whom it may concern:

Be it known that I, ALEXANDER E. KEITH, a citizen of the United States of America, and resident of Hinsdale, Du Page County, 5 Illinois, have invented certain new and useful Improvements in Telephone Transmitters, of which the following is a specification.

My invention relates to telephone transmitters and has for its object to provide a microphone structure in which the detrimental effects due to an inactive mass of granulated carbon or other comminuted material is eliminated; and in which the possibility of the occurrence commonly known as, 15 "packing," is reduced to a minimum.

In the ordinary type of transmitter employing granular carbon as a resistance varying material there is a portion of the carbon 20 which is practically inactive due to the fact that it has settled in the base of the chamber and is only slightly agitated by the movement of the diaphragm. This mass is of relatively low resistance and forms a shunt 25 to the path whose resistance is actually subject to variation, thereby reducing the amplitude of the current fluctuations. In accordance with my invention one of the electrodes, preferably the rear or fixed electrode, 30 is made considerably smaller in size than the other electrode, with the result that any current passing through the inactive material must also pass through the material undergoing the maximum agitation. 35 Although the average current values must necessarily be decreased somewhat on account of the smaller area of one of the electrodes, the range of transmission remains the same or is even in some cases increased because of the increased amplitude of the current variations, which produces a clearer 40 and more distinct articulation than has hitherto been known. The packing of the granulated carbon is prevented by so constructing 45 the containing chamber and electrodes that at least one end of the chamber, and both ends preferably, are perfectly smooth plane surfaces. In other words, at least one and preferably both of the electrodes are so designed 50 that they do not project into the carbon chamber, leaving a recess around their edges in which the carbon can pack; but on the contrary the opposite faces of the electrodes are perfectly flush with the end wall 55 of the chamber of which they form a part.

Thus the carbon is left free to rise slightly in the chamber when compressed and the tendency to pack is eliminated.

The foregoing and other useful objects are attained through means which will be 60 fully described hereinafter, reference being had to the accompanying drawing, in which Fig. 1 is a back view of a complete transmitter; Fig. 2 is a cross section on the line M—N of Fig. 1, showing a microphone construction involving a flush type rear electrode and a standard front electrode; while Fig. 3 is a modification of Fig. 2 in which both rear and front electrodes are of the flush type. 70

Referring to Figs. 1 and 2 of the drawing the reference character 1 designates the usual mouthpiece screwed into a threaded opening in the face plate 2. The face plate 2 is provided with a rearwardly projecting circular rim 5 within which is driven by special machinery and held by friction a heavy flanged ring 4, seen most clearly in Fig. 1. The metal bridge piece 3 is formed integrally with the ring 4 and acts as a support for the elements of the microphone. This latter comprises the carbon electrodes 8 and 21 and the chamber 6 partially filled with the comminuted carbon 11. The rear electrode 8 is secured to a metal disk 7 which 80 is provided with a central screw threaded stem 9. The chamber 6 is simply a plain cup drawn preferably from brass, is lined with insulating material, and is provided with a central aperture in the bottom. The 85 stem 9 passes through this hole and a corresponding bushed aperture in the bridge 3, and the nut 10 is screwed down to clamp the whole together. The chamber 6 and the nut are preferably insulated from the bridge 3 95 by means of washers of empire cloth. In order to fill the space between the sides of the rear electrode and the walls of the chamber 6, a washer 33 is provided, which may be of card board or other insulating material. 100 The outside diameter of the washer is evidently equal to the inside diameter of the chamber, while the diameter of the hole in the center is equal to the diameter of the rear electrode. The washer should fit tightly and 105 should be of such thickness that when in position it will form with the rear electrode a plane surface closing the rear end of the chamber. It is desirable that this surface be smooth and polished. 110

The front electrode 21 is affixed to a metal disk 14 which has in front a tubular portion 16 and a central screw threaded stem 22. A mica diaphragm 13 fits over the tubular portion 16 and is held in place by a conical aluminum ring or washer 15, which latter is forced over the tube 16 and is further secured by upsetting the edge of the tube. A flanged metal clamping ring 12 is driven 10 on over the rim of the chamber 6 and the mica diaphragm is securely held between the edge of the chamber and the said ring.

The usual metal diaphragm 20 rests against an insulating ring 19 on the back of 15 the face plate 2, and has at the center a hole through which is passed the stem 22. By means of nuts 17 and 18 the stem 22 is rigidly secured to the diaphragm. The damping spring comprising two members 23 and 20 24 is attached to the ring 4 by means of screws 25 and 26. The extremities of these spring members 23 and 24 press against the diaphragm 20 as shown in Fig. 2, there being 25 a felt washer interposed between the diaphragm and the end of each spring.

The foregoing describes briefly one embodiment of my invention. By referring to the drawing it will be clear that owing to the relatively small diameter of the rear 30 electrode any current flowing through the comparatively inactive material in the bottom of the electrode chamber must also pass through the active material behind the front electrode, whereby all shunting effect is 35 eliminated. It will be clear also that owing to the smooth construction of the rear wall of the electrode chamber involving the flush type rear electrode, the comminuted carbon will be free to rise in the chamber when 40 compressed, whereby the tendency to pack is greatly reduced.

In Fig. 3 is shown a modification in which the advantages pointed out above are obtained to an increased extent by employing 45 the flush type construction for both the rear and front electrodes. In this figure the microphone only is shown, together with a fragmentary portion of the bridge 3 and the main diaphragm 20. All parts except the 50 front electrode and attachments are the same as corresponding parts in Fig. 2 and hence need not be described further. Some reference characters have been attached however, to aid in identifying the parts. 55 The front electrode 40 combines in one piece an electrode and a flexible supporting diaphragm. It is stamped by dies from a metal blank and as shown in the drawing comprises a thin outer or diaphragm portion 60 and a stiff central or electrode portion, and is drilled and recessed at the center to receive the small bolt 42. The bolt 42 is held in place by the nut 41 and affords means for connecting with the main diaphragm 20. 65 The member 40 and the head of the bolt 42

are desirably gold plated to avoid corrosion; or as an alternative, the electrode may be faced with platinum foil after it and the bolt are assembled. The inner surface 43 of the flexible portion of the member 40 is painted with insulating paint or enamel of some kind in order to confine the conducting surface to the electrode portion. The member 40 is held in position by the flanged clamping ring 12. It is insulated from the ring 70 and the chamber 6 by means of a double paper washer 44, or by any other suitable means.

As illustrated, the above construction provides a cylindrical carbon chamber both inner ends of which comprise opposite, smooth, plane surfaces, the two surfaces containing, respectively, a large and small electrode area; and it has been ascertained that with such construction a transmitter 75 is obtained which embodies the advantages hitherto pointed out to the greatest possible extent.

Having described my invention, what I consider to be new and desire to have protected by Letters Patent will be more specifically pointed out in the appended claims. 90

What I claim as my invention is:

1. In a telephone transmitter, a cylindrical chamber containing resistance varying 95 material, structures having oppositely disposed, parallel plane surfaces closing the ends of said chamber, a portion only of each surface being of conducting material, the opposite conducting surfaces thus formed comprising the two electrodes of the transmitter, a diaphragm responsive to air vibrations for actuating one of said electrodes to vary the pressure on said resistance varying material, and an air space in said chamber above the 100 said resistance varying material whereby it is permitted to rise and fall as the pressure is increased and diminished.

2. In a telephone transmitter, a cell or chamber containing comminuted resistance 110 varying material, structures having parallel, plane inner surfaces forming the opposite ends of said chamber, each surface being composed part of insulating and in part of conducting material, means for making electrical connections to the two opposite conducting surfaces, whereby they act as electrodes for the transmitter, means for actuating one of said electrodes to vary the pressure on said comminuted material, and an 115 air space in said chamber above the said resistance varying material whereby it is permitted to rise and fall as the pressure is increased and diminished.

3. In a telephone transmitter, a cell or 125 chamber containing comminuted resistance varying material, structures having parallel plane inner surfaces forming the opposite ends of said chamber, each surface being composed in part of insulating and in part 130

of conducting material, the conducting portion of one surface being a substantially greater portion of the whole than the conducting portion of the other surface, and 5 means for making electrical connections to the two opposite conducting surfaces whereby they act as electrodes for the transmitter.

4. In a telephone transmitter, a cylindrical chamber containing a resistance varying 10 material, an electrode at each end of the chamber having a plane surface the area of which is less than the area of a cross section of the said chamber, oppositely disposed rings of insulating material cooperating with 15 said electrodes to form opposite plane surfaces closing the ends of said chamber, means for actuating one of said electrodes to vary the pressure on said comminuted material, and an air space in said chamber 20 above the said resistance varying material whereby it is permitted to rise and fall as the pressure is increased and diminished.

5. In a telephone transmitter, a chamber containing a resistance varying material, an 25 electrode at each end of the chamber having a plane surface partially closing the chamber, insulating material cooperating with each electrode and so disposed as to form in conjunction with the surface of the electrode 30 a substantially plane surface completely closing the chamber, means for actuating one of said electrodes to vary the pressure on said comminuted material, and an air space in said chamber above the said resistance 35 varying material whereby it is permitted to rise and fall as the pressure is increased and diminished.

6. In a telephone transmitter, a chamber containing resistance varying material, a 40 fixed electrode at one end of said chamber, insulating material cooperating with said

electrode to form a plane surface closing one end of the chamber, a movable electrode suitably supported at the other end of said chamber, a diaphragm responsive to air vibrations for actuating said movable electrode to vary the pressure on said resistance varying material, and an air space in said chamber above the said resistance varying material whereby it is permitted to rise and fall as the pressure is increased and diminished. 45

7. In a telephone transmitter, a chamber containing resistance varying material, a fixed electrode at one end of said chamber, 50 insulating material cooperating with said electrode to form a plane surface closing one end of the chamber, and a movable electrode suitably supported at the other end of said chamber, the said movable electrode having 55 a substantially greater exposed conducting surface than the said fixed electrode.

8. In a telephone transmitter, a chamber containing resistance varying material, an electrode at one end of the chamber of 60 smaller diameter than the said chamber, an insulating ring filling the space between the edge of the electrode and the wall of the chamber and cooperating with the electrode to form a plane surface closing one end of 65 the chamber, a movable electrode at the opposite end of the chamber, a diaphragm responsive to air vibrations for actuating said movable electrode to vary the pressure on said resistance varying material, and an air 70 space in said chamber above the said resistance varying material whereby it is permitted to rise and fall as the pressure is increased and diminished. 75

Signed by me at Chicago, Cook County, 80 State of Illinois, this 9th day of April, 1917.

ALEXANDER E. KEITH.
